LIFTING SLING

Lewis M. Showers, Jr., Juniata, and Ralph L.
Stiffler, Altoona, Pa.

Application May 10, 1932. Serial No. 610,448

10 Claims. (Cl. 294—67)

Our invention relates to lifting slings and more particularly to lifting slings which are adapted to be suspended from an overhead hoisting apparatus, and which are especially useful for handling shipping containers, such as less-than-carload-lot-containers, drop-bottom containers, demountable truck bodies or the like. Such containers are customarily accommodated in spaced relation in double or single rows on the floor of a freight car. To position them properly necessitates a hoisting apparatus having provision for raising, lowering and shifting a container in a truly vertical position. Otherwise, considerable difficulty is experienced in lowering a container onto its seat or raising a container from its seat without striking adjacent containers and without jamming against the container seating attachments of the car. This difficulty is more pronounced when the containers are relatively long, as is the case with the so-called "demountable truck bodies", and when the merchandise is unevenly distributed therein with the center of gravity of the load longitudinally distant from the center of the container.

Accordingly, one object of the invention is to provide in a lifting sling, designed for use with containers or the like, a pair of load carrying arms which are movable longitudinally to permit the sling to be so adjusted with respect to the object to be lifted that the center of gravity of the load will come longitudinally beneath the central suspension point of the sling, thereby preventing tilting of the object while it is suspended from the sling.

Another object of the invention is to provide in such a lifting sling means for counter-balancing the weight of the movable load carrying arms so that when no load is carried by the sling it will be maintained in a level position irrespective of the positions of the load carrying arms.

Our invention is preferably further characterized by the provision of laterally extensible load carrying arms adapted for adjustment to accommodate containers of varying sizes; and by the provision of means for automatically locking the load carrying arms to the frame of the sling incident to the raising of a load; and by other more specific novel features which will become more fully apparent from the description hereinafter of one embodiment or example of the practice of the invention. The description which follows has reference to the accompanying drawings, whereof:

Fig. I represents a side elevation of a lifting sling of our invention, showing its application to

a truck body container, the top portion of which is indicated in diagrammatic outline beneath the sling.

Fig. II represents a top plan view of the sling by itself.

Fig. III represents an end elevation of the same.

Fig. IV represents a cross section of the same, taken as indicated by the lines IV—IV of Figs. I and II.

Fig. V represents a cross section of the same, taken as indicated by the lines V—V of Figs. I and II.

Fig. VI represents a detailed cross section of the end portion of one of the load carrying arms, taken as indicated by the lines VI—VI of Fig. II.

Fig. VII represents a detailed cross section of one of the trolleys upon which a load carrying arm is supported, taken as indicated by the lines VII—VII of Fig. I.

Fig. VIII represents a detailed cross section of one of the counterweights, taken as indicated by the lines VIII—VIII of Figs. I and II.

Figs. IX and X represent enlarged detailed views of a load supporting wheeled carrier with portions thereof broken away for clearness of illustration, showing respectively the position of the yoke when no load is carried and the position of the same when carrying a load; and,

Fig. XI represents a modified or alternative form which the load carrying arms may take.

With particular reference to Figs. I, II and IV of the drawings, there is shown an example of a lifting sling of our invention, in which the frame comprises two channel beams 1 placed back to back and joined by plates 2 and 3 at the top and bottom, respectively, to form in effect an I-beam, the top flanges whereof are designated at 4 and the bottom flanges whereof are designated at 5. Attached to the top of the frame at the center thereof, there is a lifting eye 6 which is adapted to be suspended from a hook 7 of an overhead hoisting apparatus. The particular type of overhead hoisting apparatus to be used forms no part of our invention, but it is contemplated that the frame of the lifting sling will be freely suspended from the overhead hoisting apparatus rather than rigidly attached thereto.

Supported on the bottom flanges 5 of the I-beam frame, with capacity for longitudinal movement thereon, there are two wheeled carriers from which load carrying arms, comprehensively designated 8a and 8b are suspended, there being one such load carrying arm at each

end of the frame. Each wheeled carrier comprises a pair of trolleys 9 on opposite sides of the frame joined together by a yoke 10 which straddles the bottom flanges 5 of the frame. 5 Each trolley in turn comprises two wheels 11 and semi-elliptical leaf springs 12 curled at their ends to engage the axles 13 of the wheels and to form a span therebetween. As shown in Fig. VII, the wheels 11 are provided with ball bearings 14, and each axle 13 is in the form of a bolt having a nut 15 thereon for maintaining the leaf springs 12, the wheel 11, and the ball bearing 14 in proper assembled relation.

The yoke 10 of each wheeled carrier is in 15 the form of a casting having at the top portion upstanding ribs 16 which define channels for the accommodation of the springs. Each such channel, as shown in Fig. IV, has fitted thereon a pad 17 attached to the yoke 10 by a bolt 18, and the springs 12 are thus securely fastened 20 to the yoke. At the base portion of each yoke 10, provision is made for a fulcrum pin 19 to which a V-shaped connecting member 20, which is a part of a load carrying arm 8a, 8b, is pivoted. 25 The yoke 10 is interiorly configured to provide ample clearance from the bottom flanges 5 of the I-beam frame, and on one of its inner vertical surfaces 22, there is mounted a pair of swinging pawls 23. Each pawl 23 terminates in 30 a tooth 24 which is adapted upon the flexing of the springs 12 under load to engage a notched member or rack 25 disposed along the web of the I-beam frame, in the manner shown in Fig. X, wherein a portion of the yoke 10 is broken away to show the position of a pawl. There is one such rack 25 at one side of the frame extending from the center thereof to the end, and another such rack at the opposite side extending from the center of the frame to the 35 other end. When no load is carried by the sling, the yoke 10 is raised by the springs 12 to the position shown in Fig. IX, in which case inclined surfaces 26 of the yoke engage lugs 27 on the swinging pawls, causing the pawls to be 40 raised with the yoke and hence to be free from engagement with the rack 25.

From the above description it will be apparent 45 that the bottom flanges 5 of the channel beams 1 afford a track upon which the wheeled carriers 50 are independently movable lengthwise of the frame; and it will be further apparent that the wheeled carriers supporting the load carrying arms 8a, 8b are normally unobstructed in their movement, but when a load is carried on the arms 8a, 55 8b, incident to the resulting downward flexure of the springs 12, the wheeled carriers are locked to the frame by the engagement of the fixed pawls 23 with the teeth of the rack 25. At the outer 60 end of each rack 25, there is provided a block 30, shown clearly in Figs. I and V, which serves as a stop limiting the travel of the wheeled carrier. As 65 a wheeled carrier approaches the end of the frame, the ledge 31, shown clearly in Figs. I and IV, strikes the block 30 and prevents further movement.

At each end of the I-beam frame there is a 70 transverse plate 32. Adjacent to each plate 32 there are brackets 33 which afford a bearing for the shafts 35 of sheaves 36. The sheaves 36 are supported on ball bearings 37, as shown in Fig. V. On the top flanges 4 of the I-beam frame, there are provided movable counterweights 38a and 38b for balancing the weight of the load carrying arms 8b, and 8a, when a load is carried by 75 the lifting sling in order to maintain the sling

in a level position irrespective of the positions of the load carrying arms. Each counterweight 38a, 38b may take the form shown in Fig. VIII in which the same comprises a rectangular block having depending ears 39 which serve as guides 80 and recessed portions 40 in which rollers 41 are housed, the rollers 41 traveling on the top surface of the upper flanges 4 of the channel beams, and the ears 39 guiding the movement of the counterweight by engagement with the edges of the flanges 4. Each counterweight 38a, 38b is centrally slotted at 42 with the slot terminating in an inclined wall 43 so that the wings of the lifting eye 6 may enter the slot permitting the counterweight to be moved inward from the ends of the frame to a point very near the center thereof. 90

Each counterweight 38a, 38b is also recessed at the top thereof, as indicated at 44, to provide a cavity which may be filled with lead or other material of the desired weight to effect the final 95 balancing adjustment so that the frame will be in equilibrium with each counterweight 38a, 38b compensating for the weight of the load carrying arm 8a, 8b at the opposite end of the frame. 100

The counterweight designated at 38b is connected by a wire cable 45b with the load carrying arm 8b, and similarly the counterweight 38a is connected by a wire cable 45a with the load carrying arm 8a. Thus with reference to Fig. I, it will be seen that the wire cable 45b is attached as indicated at 46 to the top of the yoke 10 of the load carrying arm 8b. The cable 45b passes around a sheave 36 at the end of the frame shown at the right hand of the figure; then runs along the top of the frame through the counterweight 38a, passing freely through this counterweight; then runs through the counterweight 38b to which it is secured by a clamp 47; then passes around a sheave 36 at the opposite end of the frame; then passes through an eye 48 at the top of the yoke 10 of the load carrying arm 8a; and ultimately terminates in a turnbuckle 49 at the load carrying arm 8b. The other cable 45a takes a similar course at the opposite side of the frame, connecting the load carrying arm 8a with the counterweight 38a. 115 Accordingly, it will be apparent that when no load is carried on the lifting sling, the load carrying arms 8a, 8b, irrespective of their positions, will be automatically balanced, and the sling thus maintained in equilibrium. 120

The load carrying arms 8a, 8b may take the form shown in Figs. I, II and III, in which case each arm comprises the pivoted connecting member 20, wire cables 50 terminating in hooks 51, and an extensible spreader for varying the distance between the hooks 51. The spreader comprises interfitting tubular members 52 and 53 which are correspondingly internally and externally threaded. On the tubular member 52, hand wheels 54 are provided. By turning the hand wheels 54 in one direction, the tubular members 53 are caused to be extended laterally; and by turning the handles 54 in the opposite direction, the tubular members 53 are contracted. The spreader terminates at each end in a head 55 grooved at 56 to receive the wire cable 50. Clamps 57 secure the cables to the spreader heads 55. 135

Alternatively the load carrying arms may take the form incomprehensively designated at 8c in Fig. XI. In this form a similar connecting member 20 is employed for pivotal attachment to a wheeled carrier. Wire cables 58 leading from the connecting member 20 join the ends of a spreader 59 and form therewith a triangle. The 145 spreader 59 may be suitably made of seamless tub- 150

ing with heads 60 of expanded formation. Each head 60 of the spreader 59 is slotted, as indicated at 61, and provided with three spaced notches 62 at the slot 60. Movable in the slot 60 at each end of the spreader 59, there is a link 63 which carries a hook 64. In an obvious manner, the distance between the two hooks 64 of the load carrying arm 8c may be varied within limits by moving the links 63 from one notch 62 to another.

In Fig. I there is indicated diagrammatically at A, the top portion of a so-called "demountable truck body" having fixed attachments B near the corners thereof engaged by the suspension hooks 51 of the load carrying arms 8a and 8b. With the truck body A disposed in relation to the lifting sling, as shown in Fig. I, the center line CL of the truck body is somewhat remote longitudinally from the central suspension point of the I-beam frame, as indicated at x. Assuming that the line CG represents a transverse plane through the center of gravity of the truck body A, the lifting sling would be positioned as shown in the drawings, with the load carrying arms 8a and 8b spaced unequally from the center of the I-beam frame so as to cause the central suspension point of the frame to come longitudinally above the center of gravity of the truck body. When the truck body is thus engaged, it may be raised without tilting and hence without danger of striking adjacent truck bodies or of jamming against guides on the vehicle platform from which it is raised.

From the above description it will be apparent that by employing load carrying arms such as shown at 8a and 8b, or at 8c, which are independently movable, the lifting sling may be adapted for use with containers or truck bodies of varying sizes, and the load carrying arms may be so adjusted, by trial and error, as to permit a container to be suspended with the hook of the overhead hoisting apparatus longitudinally over the center of gravity of the container. When a container is thus engaged, and the lifting sling is raised, the weight of the container causes the springs 12 of the trolleys 9 to flex downward which locks the load carrying arms 8a, 8b against longitudinal movement of the I-beam frame. After a container has been hoisted, shifted and lowered to a new position, and the lifting sling is disengaged therefrom, when the lifting sling is raised free of the load, it will be maintained in equilibrium by the action of the counterweights as previously described.

While we have described one example of the practice of our invention, showing, however, alternative arrangements for the load carrying arms, it will be apparent that various changes may be made in the form of the lifting sling herein described and illustrated without departing from the spirit of our invention as defined in the claims hereto annexed, and it will be further apparent that certain features of the invention may at times be used to advantage without a corresponding use of other features.

While in railroad parlance a distinction is made between "containers" and "truck bodies", it is to be understood that the word "container" as used in this application is used in its generic sense and is intended to include so-called "truck bodies", as well as other particular forms of containers.

Having thus described our invention, we claim:

1. A lifting sling for hoisting rectangular containers comprising a frame adapted to be suspended at its center from an overhead hoist, load

carrying arms movable independently on said frame, and means for counterbalancing each said arm whereby the frame is maintained in level position when no load is carried thereon, irrespective of the positions of said arms.

2. A lifting sling for hoisting rectangular containers comprising a frame adapted to be suspended at its center from an overhead hoist, load carrying arms movable independently on said frame, and counterweights movable with said arms to maintain said frame in level position when no load is carried thereon, irrespective of the positions of said arms.

3. A lifting sling for rectangular containers, comprising a frame adapted to be suspended at its center from an overhead hoist, load carrying arms movable independently on said frame, a counterweight for each said arm disposed at the opposite end of the frame therefrom, and means connecting said counterweights with said arms whereby the counterweights are automatically movable with said arms to maintain said frame in level position when no load is carried thereon.

4. A lifting sling for rectangular containers comprising an I-beam frame adapted to be centrally suspended from an overhead hoist, laterally extending load carrying arms movable longitudinally on said frame, and counterweights for each said arm automatically movable to maintain said frame in level position when no load is carried thereon irrespective of the positions of said arms.

5. A lifting sling for rectangular containers comprising a frame adapted to be suspended from an overhead hoist, and load carrying arms movable longitudinally on said frame, said arms being normally unobstructed in their movement but being adapted to be locked to the frame by the weight of the load when a container is raised by said arms.

6. A lifting sling comprising a frame adapted to be suspended from an overhead hoist, and load carrying arms movable on said frame, said arms being normally spring supported with capacity for sliding movement on said frame but being adapted to be locked to the frame by the weight of the load when a load is raised thereby.

7. A lifting sling comprising a frame adapted to be suspended from an overhead hoist, said frame having a longitudinal track thereon and a notched member adjacent to said track, a carrier movable on said track, load carrying members on said carrier, and means whereby said carrier and load carrying members are normally unobstructed in their movement along said track but are adapted to be locked to said notched member by the weight of the load when a load is raised thereby.

8. A lifting sling comprising a frame adapted to be suspended from an overhead hoist, said frame having a track thereon and having a notched member adjacent to said track, a carrier movable on said track, load carrying arms suspended from said carrier, said carrier including a spring for supporting said load carrying arms, and means whereby said carrier becomes locked to said notched member when said spring is flexed under load.

9. A lifting sling comprising a frame adapted for suspension from a hoist, a track extending the length of said frame, a carrier running on said track, said carrier including wheels connected by a leaf spring, a load carrying arm supported on said spring, a notched member adja-

cent said track, and a tooth on said carrier normally out of engagement with said notched member but adapted to engage said notched member when said spring is flexed incident to the raising of a load by said arms.

10. A lifting sling for containers of varying sizes comprising a frame adapted to be suspended

from an overhead hoist, and a load carrying arm movable longitudinally on said frame including interfitting tubular members extensible by relative rotation for adjusting said arm to accommodate containers of varying widths.
